UNITED STATES PATENT OFFICE.

CLAUDE DORNIER, OF FRIEDRICHSHAFEN, GERMANY, ASSIGNOR TO THE FIRM:
LUFTSCHIFFBAU ZEPPELIN GESELLSCHAFT MIT BESCHRANKTER HAFTUNG, OF
FRIEDRICHSHAFEN, GERMANY.

LIGHT-WEIGHT GIRDER.

Application filed June 28, 1920, Serial No. 392,563, and in Germany May 4, 1917.

(GRANTED UNDER THE PROVISIONS OF THE ACT OF MARCH 3, 1921, 41 STAT. L., 1313.)

My invention refers to girders which combine small weight with great strength and can be manufactured with ease, so that they are suitable for wholesale manufacture more especially for the purpose of air craft construction.

In the novel girder, which is preferably made of light metal, a middle web of sheet metal bent in zigzag fashion has its longitudinal edges rigidly fixed to flange plates extending vertically in regard to the surface of the middle web. The width of the flange plates does not materially exceed the depth of the corrugations formed in the middle web which is thus easily accessible from both sides and in this way distinguishes favorably from girders whose webs consist of a row of adjoining cells. Besides, it braces the flange plates in a most effective manner and the danger of buckling and bending is thus effectively avoided.

The drawings attached to this specification and forming part thereof illustrate two modifications of a girder embodying my invention by way of example.

Fig. 1 is a perspective view of a plate girder with plane flange plates and

Fig. 2 is a similar view of a girder with corrugated flange plates, the parts being shown unassembled.

In the modification shown in Fig. 1 the middle web is formed by a thin corrugated sheet metal strip *a* having its lateral edges provided with tongues *b* deflected at right angles to said strip *a*, plane flange plates *c* being fixed to the tongues *b* by riveting or welding.

In the modification illustrated in Fig. 2 *d* is the zigzag-shaped sheet metal strip forming the middle web. *f*, *f* are the top and bottom flange plates each of which is

braced by two longitudinal grooves *g*. Angle strips *e*, *e* are riveted or otherwise secured to both sides of the middle web *d* so as to laterally project above and below it, 45 respectively, and the flange plates *f* are secured by riveting or otherwise to the outer surfaces of the angle strips *e*. At the ends the girder is reinforced by means of strong plates *h* extending between and fixed to the 50 angle strips on each side of the middle web.

Preferably, thin steel plate or light metal sheet is employed, but it is also possible to produce girders which at least partially consist of wood, cellulose or other artificial 55 products. According to the constructional material employed, the various parts of the girder can also be united with each other by gluing or bolting or in similar manner.

I wish it to be understood that I do not 60 desire to be limited to the exact details of construction shown and described, for obvious modifications will occur to a person skilled in the art.

I claim:—

1. In a composite sheet metal girder in combination, two sheet metal plates disposed substantially in parallel, a separate sheet metal web bent zigzag fashion arranged intermediate said plates in such manner that 70 the zigzag bends lie in vertical planes and means for fixing said web to said plates.

2. In a composite sheet metal girder in combination, two longitudinally grooved sheet metal plates disposed substantially in 75 parallel, a separate sheet metal web bent zigzag fashion arranged intermediate said plates and angle strips fixed to said web and to said plates, respectively.

In testimony whereof I affix my signature.

CLAUDE DORNIER.
